CIGAR LIGHTER

John Holtzman, New York, N. Y.

Original application May 22, 1929, Serial No. 365,013. Divided and this application December 21, 1933, Serial No. 703,376

17 Claims. (Cl. 67--4.1)

This application is a division of my copending application for patent for cigar lighter, Serial No. 365,013, filed May 22, 1929.

This invention relates to pocket cigar and cigarette lighters, and particularly, to the type of so-called "automatic" lighters wherein a light is produced automatically on the release of a controlling member, or merely on lifting the lighter.

My invention contemplates the provision of economical, simple and effective means for automatically actuating the spark-producing mechanism usually employed in devices of this character and for simultaneously uncapping the wick.

My invention contemplates also the provision of mechanism self-operating upon the lifting of the lighter above the supporting surface therefor.

The various objects of my invention will be clear from the description which follows, and from the drawing, in which,

20 The figure is a vertical section of my improved lighter, wherein the parts are operated entirely automatically.

In that practical embodiment of my invention which I have illustrated, I have shown a form of my invention wherein all of the parts are automatically operated at all times on the lifting of the lighter from the supporting surface therefor. The container 70 is provided with a base as 71 which conceals most of the operating parts. Said 25 casing or container 70 is further provided with a plunger tube 72 in which the plunger 73 is mounted for vertical reciprocation. A spring as 74 is arranged about said plunger, and serves to urge said plunger toward the lowermost position 30 thereof. On the top of the casing is mounted the wheel cover and wick capping frame 75, carrying the cap 76 for covering the wick, and preventing the evaporation of fuel therethrough.

35 Mounted in the sides of said frame and serving as a pivot therefor is the wheel shaft 77 supported in suitable ears 99 upstanding from the top of the casing. On the shaft 77 is mounted the abrading wheel 47. A suitable ratchet disc (as shown in Figs. 1 and 5 of my parent application Serial No. 365,013, now Patent No. 1,944,177), serves to operatively connect the frame with the abrading wheel, so that rotation of said frame in the proper direction causes the abrading wheel to rotate and to strike the sparks from the block 33 of pyrophoric material. Said block is mounted in the tube 78, closed by the removable screw 79 which is pressed into engagement with the abrading wheel by means of the spring 80.

40 The plunger 73 is operatively connected to the frame 75 by any suitable means such as for ex-

ample, by means of the pin 81 passing through the slot 82 of the frame. It will be seen that when the plunger 73 is released for downward reciprocation under the influence of the spring 74, the pin 82 moving downwardly rotates the frame 75 about the shaft 77 in the proper direction to cause the abrading wheel to rotate and to produce sparks to light the wick, while simultaneously uncapping the wick.

Said plunger 73, however, is normally maintained in its uppermost position to hold the frame 75 in wick capping position, by any suitable latching means adapted to be released on the raising of the lighter from the supporting surface therefor. As illustrated, said means takes the form 45 of a latch 83, urged by the spring 84 into the shallow slot 85 near the lower end of the plunger. Said latch and spring are carried by the slide 86 supported by the lugs 87 which are in turn secured to the bottom of the casing or container 70. A spring as 88 acts upon said slide and tends 50 to urge said slide toward the left, so as to release the latch 83 from the slot therefor. For normally preventing the withdrawal of the slide and therethrough of the latch toward the left, I 55 prefer to mount a cam as 89 in engagement with the end 90 of said slide. Said cam is supported by the shaft 91 mounted in the lugs 87 which extend from the bottom of the casing. Secured to and extending from said shaft 91, is the lever 60 93 terminating in a suitable weight as 94. Both 50 said weight and the lower end of the plunger 73 may be covered with suitable soft material such as felt for preventing injury or marring of the surface on which the lighter rests.

65 As the lighter is lifted from the supporting surface, the weight 94 being no longer supported, drops and thereby rotates the cam 89, through the lever 93 and the shaft 91, out of engagement with and thereby releasing the end 90 of the 40 slide 86.

Said slide when so released, is urged by the spring 88 toward the left carrying with it the latch 83 a sufficient distance to disengage the latch from the slot 85. The plunger 73 is thereby 45 released and drops under the action of the spring 74, thereby rotating the frame 75 and causing the abrading wheel to light the wick. I do not, however, wish to be understood as limiting myself to the specific locking means shown for preventing operation of the spark-producing mechanism, and said means is intended to be merely 50 illustrative.

60 To return the parts to their normal positions, the lighter is merely again placed back on the 55

supporting surface whereupon the plunger 73 is raised as is the weight 94, causing the cam 89 to push the slide 86 toward the right and causing the latch 83 to reengage the slot 85 and thereby to hold the plunger in its uppermost position. On the raising of the plunger, the frame 75 is returned to closed position to extinguish the light and to cap the wick.

It will be seen that for pocket lighters, the lever 93 may be operated directly by the finger of the user to turn the cam 89 and to effect operation of the lighter.

It will be understood that I do not intend to limit myself to the specific form of my invention shown and described but intend to claim my invention as broadly as may be permitted by the state of the prior art and the terms of the appended claims.

I claim:

- 20 1. In a pyrophoric lighting mechanism, a casing, a wick projecting from the top wall of the casing, two relatively movable members having operative connection with each other, one of which is a sparking wheel and the other of which 25 is a snuffer-carrying member disposed for pivotal movement above the top wall of said casing, a block of pyrophoric material yieldingly supported against said wheel, a plunger mounted in said casing normally projecting above the top 30 wall of said casing and having an operative connection with the snuffer-carrying member for swinging said member on its pivot, said mechanism including a spring adapted to be tensioned by the movement of said plunger in one direction, for swinging said snuffer-carrying member to operate the wheel, a spring-pressed latch in 35 said mechanism adapted to retain the snuffer-carrying member in position to cover the wick, and against the force of said spring, said latch 40 being arranged to lock said snuffer-carrying member against movement automatically upon the predetermined projection of said plunger above the top wall of the casing and upon the movement of said plunger upwardly.
- 45 2. In a pyrophoric lighting mechanism, a casing, a wick projecting above the top wall of the casing, two relatively movable members having an operative connection with each other, one of which is a sparking wheel and the other is a 50 snuffing member and both rotatably mounted above the top wall of the casing, a plunger mounted in said casing and normally projecting above the top of the casing and having an operative connection with the snuffing member for swinging said member on its pivot, a spring in said mechanism adapted to be tensioned by the movement of said plunger for actuating said snuffing member to rotate the wheel, a spring-pressed latching member in said mechanism arranged to maintain 55 said snuffing member in closed position to cover the wick and weighty means for releasing said latching member to swing said snuffing member in the direction to turn the wheel and light the wick, said means being inoperative when the 60 casing rests on a supporting surface and being operative to release the latching member when the casing is lifted from said surface.
- 70 3. In a light-producing mechanism, a casing, a wick projecting above the top wall of said casing, an abrading wheel rotatably mounted above the top of the casing, a pyrophoric element yieldingly supported against the wheel, a snuffing member pivotally mounted above the top wall, and having operative connection with said wheel, a spring for operating said mechanism, a recip-

rocable push device acting on said spring normally to compress the spring preparatory to operation of the mechanism, an operative connection between said device and the snuffer member, a releasable latching member located in said mechanism normally to prevent the action of said spring means, and pivotally mounted means acting on said latch to release said latch and to cause operation of the mechanism.

4. In a pyrophoric lighter, a casing, a wick 10 projecting above the top wall of said casing, an abrading wheel rotatably mounted above the top wall of the casing, a snuffing member pivotally mounted above the top of the casing and having operative connection with said wheel, a push 15 plunger mounted in said casing and extending above the top of the casing, a spring interposed between said plunger and casing, said plunger having a slidable connection with the snuffing member to actuate the same, a latching member 20 adapted to lock said snuffing member in closed position against the wick until a predetermined state of tension of said spring is produced, a pivotally mounted member mounted in said casing and acting on said latch to release said spring for 25 action to swing said snuffing member upwardly and thereby to operate the wheel to light the wick.

5. In a cigarette lighting device, a casing, a wick projecting above the top wall of said casing, an abrading wheel rotatably mounted above the top wall of the casing, a lever pivotally supported above the top wall of the casing, a pyrophoric element pressed against the wheel, said lever carrying a cap on one end thereof to cover the wick, and having an extension at the other end 35 thereof, a spring-operated plunger mounted within said casing and having an operative connection with said extension of the lever to operate the device, a latch member mounted in said device normally to lock the cap against the wick, and means responsive to the lifting of the device off a supporting surface therefor for operating said latch member to remove the cap from the wick and simultaneously to operate the wheel to light the wick.

6. A lighter comprising a casing, a wick, an abrading wheel for generating sparks to light the wick revolubly supported by said casing, a capping member for covering the wick pivotally supported by said casing, a spring pressed plunger mounted on the top of said casing and extending into said casing, a spring acting on the plunger, a slot and pin connection between said plunger and said capping member, a latching member mounted in said casing and adapted to lock said capping member in snuffing position against the wick, and means to actuate said latching member to release the spring to operate the lighter.

7. A cigarette lighting device comprising a casing, a wick, a frame upstanding above the top 60 wall of said casing, a sparking wheel rotatably mounted in said frame, a lever pivotally mounted in the frame, said lever having means to actuate the sparking wheel, a spring-actuated plunger projecting above the top wall of the casing and 65 having a slidable connection with said lever, a spring-operated latch in the device, means to actuate said latch whereby the wick may be ignited, a cap carried by said lever to cover the wick upon the upward movement of said plunger above the 70 top wall of said casing.

8. In a lighter, an abrading wheel, a wick, a pivoted frame normally covering said wheel and said wick, means for swinging said frame to simultaneously uncover said wick and rotate said 75

wheel, and weighty means adapted to rest on a supporting surface for maintaining said frame swinging means in inoperative position and for releasing said operating means when the lighter is removed from the supporting surface therefor.

5 9. In a lighter, spark-producing and flame-extinguishing means, means for operating said spark-producing and extinguishing means automatically, and means for locking said operating 10 means and for automatically releasing said means on the lifting of said lighter away from a supporting surface therefor.

10 10. In a lighter adapted to rest on a supporting surface, spark-producing means and means 15 responsive to the lifting of the lighter off said surface for preventing the operation of the spark-producing means while the lighter rests on the supporting surface and responsive to the lifting of the lighter off said surface to cause the operation 20 of the spark-producing means including a spring-pressed latch, and gravity means for operating the latch.

15 11. In a lighter adapted to rest on a supporting surface, spark-producing means and means 25 for maintaining said spark-producing means in inoperative position while the lighter rests on the supporting surface and for releasing said spark-producing means automatically for operation when the lighter is lifted including a latch 30 and means adapted to engage the surface for operating the latch.

20 12. In a lighter adapted to rest normally on a supporting surface, spark-producing means, gravity means for automatically causing operation 35 of the spark-producing means when the lighter is lifted off said surface, and means for normally locking the spark-producing means against operation.

25 13. In a lighter, spark-producing and flame extinguishing means, and means for automatically operating said spark producing and extinguishing means on the alternate lifting of said lighter away from and the resting of said lighter on a supporting surface therefor.

30 45 14. A lighter including a casing, a rod slidably mounted by said casing, means whereby said rod normally tends to extend below said casing, a wick extending from the casing, an abrading wheel, a pivoted frame normally covering said 45 wheel and said wick, and means connecting said frame with said wheel whereby the frame will automatically uncover the wheel and the wick

upon the lighter being lifted from a supporting surface therefor.

5 15. In a lighter, spark-producing means including an abrading wheel, wick snuffer means, and means responsive to the lifting of the lighter 5 from a supporting surface for simultaneously rotating the abrading wheel and for moving the snuffer means to wick uncapping position.

10 16. In a lighter, a casing, a wick, an abrading wheel, a snuffer member for sealing the wick, said 10 wheel and snuffer member being located over the casing, a member arranged for vertical reciprocation in the casing, said wick and reciprocating member being located on opposed sides of the wheel, the snuffer member covering the wheel 15 and wick and being pivoted on the same axis as the wheel, an operative connection between the snuffer member and the wheel, a projection on the reciprocating member for engaging and rotating the snuffer member to rotate said snuffer member to seal the wick when the reciprocating member is moved upwardly to a limiting position in one direction, spring means for urging the abrading wheel to rotate, a spring-pressed 20 latch for preventing rotation of the snuffer member and the wheel under the influence of the spring means when the wick is sealed by the snuffer member, said latch being held in released position by said reciprocating member when said member is moved downwardly a pre-determined distance from said limiting position.

25 17. In a lighter, a casing, a wick, spark-producing means including an abrading wheel, a snuffer member for the wick, said wheel and snuffer member being located over the casing, 35 a member arranged for vertical reciprocation in the casing, said wick and member being located on opposed sides of the wheel, said snuffer member being pivoted on the same axis as the wheel, means for operatively connecting the snuffer to 40 the spark-producing means, a projection on the reciprocating member for engaging and rotating the snuffer member to cap the wick, a spring for operating the spark-producing means, a spring-pressed latch in the path of and for engagement 45 with the reciprocating member for preventing operation of the spark-producing means by said spring until said latch is released and then permitting said spring to rotate the snuffer member to expose the wick and to rotate the abrading 50 wheel to produce sparks.

JOHN HOLTZMAN.
